VACUUM COOLING APPARATUS

Le Roy A. Droeher, Bala-Cynwyd, Pa., assignor
to C. H. Wheeler Manufacturing Co., Philadelphia, Pa., a corporation of Pennsylvania

Application June 7, 1946, Serial No. 675,259

6 Claims. (Cl. 62—152)

1

This invention relates to vacuum cooling apparatus and has particular reference to such apparatus in which evacuation is effected through the use of steam jet ejectors.

Steam jet refrigerating apparatus is particularly useful and economical where large quantities of evaporable liquids are to be used for cooling purposes as, for example, in air conditioning. However, certain characteristics of this type of apparatus make it difficult to secure control of temperature within narrow limits.

The capacity of a steam ejector is fixed by the initial design characteristics and its capacity cannot be properly regulated by throttling the steam flow. Accordingly, there is substantially no flexibility in handling different refrigeration loads for any given chilled liquid temperature. For example, when a steam ejector is associated with a flash evaporator there exists a characteristic of operation which involves a substantially linear relationship between the quantity of cooled liquid which is delivered and the temperature thereof when the entering liquid is at constant temperature. For example, if at rated flow of cooled liquid a particular installation will give rise to a 50° F. temperature of the cooled liquid, then a flow of liquid corresponding to 85% of the rated flow may give rise to a temperature of 45° F. whereas 115% of rated flow may involve a temperature of 55° F., the indicated linear relationship existing both within and without these limits. Similarly for a fixed flow, the temperature of the cooled liquid will bear a definite relationship to the temperature of the liquid entering the evaporator. As a consequence, therefore, the temperature of the delivered liquid is obviously critically dependent upon the refrigeration load.

It sometimes happens that the requirements are such as to demand a substantially constant temperature with varying refrigeration loads. It is the broad object of the present invention to provide a simple system whereby very close temperature control may be secured in a system of the type indicated while permitting substantial latitude in the quantity or initial temperature of the liquid which is being chilled.

This and other objects particularly relating to details of construction and operation will become apparent from the following description read in conjunction with the accompanying drawing in which the figure represents diagrammatically a vacuum cooling system embodying the principles of the invention.

There is indicated at 2 a flash evaporator of conventional type consisting of an enclosure

2

within which an evaporable liquid such as water is evaporated under vacuum with attendant cooling. This evaporator is fed with liquid from a line 4 which may be either a make-up line or more usually a return line for the liquid from the point of heat transfer thereto, suitable make-up to take care of evaporation being provided in conventional fashion, or, if dehumidification is involved, there being proper provision for elimination of excess liquid. The liquid from the line 4 which is to pass to the evaporator is controlled in the usual fashion by a valve 6 under the control of a float 8 which maintains substantially constant the liquid level in the evaporator. The incoming liquid is sprayed into the evaporator through the usual nozzles 10. From a low point in the evaporator the chilled liquid is withdrawn through a line 12 by a pump indicated at 14 and is delivered thereby through the discharge line 15 to the point of use.

The evaporator illustrated in the figure has associated with it a plurality of steam jet ejectors individually connected to the evaporator through selectively operable valves 18, these ejectors being fed with steam in the usual fashion to produce a vacuum, for example, of the order 29.7 inches in the case of a 30 inch barometer.

To the extent so far described the system is substantially conventional. Various combinations of ejectors, which may have suitable different capacities, may be used to maintain the proper outflow temperature of the liquid from the evaporator. Under ordinary conditions of operation there would then exist the characteristics described above, i. e., the temperature of the delivered liquid would depend upon the quantity delivered in such fashion that constant temperature could be maintained only for a particular quantity delivered when any particular combination of ejectors is used.

In accordance with the present invention a thermostat bulb 20 responds to the temperature in the delivery line from the pump and through a suitable control device 26 of conventional type serves to control a valve 24 in a bypass line 22 running from the supply line 4 to a point such as indicated at 28 in the evaporator at a low level therein so that the static head prevents flash evaporation of the warm water which flows through the bypass. As will be evident, instead of permitting this warm water to mingle with the chilled water in the evaporator the bypass may run directly to the pump intake or to any point intermediate the evaporator and the pump intake.

In the operation of this system assume that one or more of the steam ejectors are in operation, the capacity of the ejectors being such as to be capable of maintaining for a particular delivery of liquid a temperature less than that required, i. e., a temperature less than that for which the thermostat is set. Under such conditions the thermostat, which is desirably of a sensitive type, will open the bypass valve 24 to such extent as to provide a proportion of flow through the bypass related to that entering the evaporator as to maintain at the output of the pump the desired temperature, i. e., only a certain proportion of the delivered liquid passes through the evaporator nozzles to be chilled thereby to a temperature below that required, while the remaining liquid bypasses the evaporator to the pump intake, being mixed in the pump with the chilled liquid. If now the flow demand is reduced an automatic readjustment takes place, the proportion of the bypassed liquid increasing by further opening of the valve 24 with attendant decrease of flow through the valve 6 so that the temperature is maintained. With increase of flow the opposite action occurs, the proportion of liquid flowing through the bypass being reduced so that nevertheless the temperature of the liquid delivered by the pump remains substantially constant.

The foregoing operation may theoretically continue until the quantity demand is such that the jet ejectors in operation will be no longer able to maintain the desired chilled condition of the liquid even with the bypass completely closed. Before this condition is reached, therefore, another ejector must be cut into the system. While the introduction or removal of the various ejectors may be effected automatically, by tie up with the condition of substantial closing or full opening of the bypass valve 24, this is not generally required since an attendant may cut the ejectors in or out as indicated by a suitable signal controlled in conjunction with the bypass valve, the flow through which may be observed either from the valve position or by the incorporation of a suitable flowmeter. In any event, while through a full range of operation different numbers of ejectors may be required, nevertheless in the individual ranges of operation corresponding to particular numbers of ejectors a smooth and accurate control of the temperature is provided irrespective of variations in the quantity delivered by the pump 14. Thus refrigeration capacity requirements intermediate between individual ejectors or plural combinations thereof may be obtained in accordance with the invention. It will be evident that the range of variation of temperature will depend solely upon the sensitivity of the thermostat control, control being easily possible to a fraction of a degree.

It will, of course, be understood that the ejectors or boosters may be arranged and operated in conventional fashion in conjunction with conventional condensing equipment and other devices of usual type.

What I claim and desire to protect by Letters Patent is:

1. In combination, an evaporator, means for evacuating said evaporator, a supply line to said evaporator, a delivery line from said evaporator, a bypass connecting said supply line to said delivery line, flow control means mounted in said supply line between said evaporator and the point of connection of said bypass with said supply line, flow control means mounted in said bypass

line, and means controlling said second mentioned flow control means regulating the flow of liquid through the bypass to maintain the temperature of the delivered liquid substantially constant.

2. In combination, an evaporator, means for evacuating said evaporator, a supply line to said evaporator, a delivery line from said evaporator, a bypass connecting said supply line to said delivery line, flow control means mounted in said supply line between said evaporator and the point of connection of said bypass with said supply line, flow control means mounted in said bypass line, and means controlling said second mentioned flow control means regulating the flow of liquid through the bypass to maintain the temperature of the delivered liquid substantially constant, the exit from said bypass being at a location under sufficient static head to prevent flashing.

3. In combination, an evaporator, means for evacuating said evaporator, a supply line to said evaporator, a delivery line from said evaporator, a bypass connecting said supply line to said delivery line, flow control means mounted in said supply line between said evaporator and the point of connection of said bypass with said supply line, means responsive to the liquid level in the evaporator controlling said flow control means, flow control means mounted in said bypass line, and means responsive to the temperature of the liquid in said delivery line beyond the point of its connection with said bypass controlling said second mentioned flow control means regulating the flow of liquid through the bypass to maintain the temperature of the delivered liquid substantially constant.

4. In combination, an evaporator, a plurality of individually controllable means for evacuating said evaporator, a supply line to said evaporator, a delivery line from said evaporator, a bypass connecting said supply line to said delivery line, flow control means mounted in said supply line between said evaporator and the point of connection of said bypass with said supply line, flow control means mounted in said bypass line, and means controlling said second mentioned flow control means regulating the flow of liquid through the bypass to maintain the temperature of the delivered liquid substantially constant.

5. In combination, an evaporator, a plurality of individually controllable steam ejector means for evacuating said evaporator, a supply line to said evaporator, a delivery line from said evaporator, a bypass connecting said supply line to said delivery line, flow control means mounted in said supply line between said evaporator and the point of connection of said bypass with said supply line, flow control means mounted in said bypass line, and means controlling said second mentioned flow control means regulating the flow of liquid through the bypass to maintain the temperature of the delivered liquid substantially constant.

6. In combination, an evaporator, a plurality of individually controllable means for evacuating said evaporator, a supply line to said evaporator, a delivery line from said evaporator, a bypass connecting said supply line to said delivery line, flow control means mounted in said supply line between said evaporator and the point of connection of said bypass with said supply line, means responsive to the liquid level in the evaporator controlling said flow control

means, flow control means mounted in said bypass line, and means responsive to the temperature of the liquid in said delivery line beyond the point of its connection with said bypass controlling said second mentioned flow control means regulating the flow of liquid through the bypass to maintain the temperature of the delivered liquid substantially constant.
